(57) **CLAIM**

The ornamental design for a cell filter, as shown and described.

DESCRIPTION

The patent or application file contains at least one drawing executed in color. Copies of this patent or patent application publication with color drawing(s) will be provided by the Office upon request and payment of the necessary fee.

1. Cell filter

1.1 : Perspective

1.2 : Perspective

1.3 : Front

1.4 : Top

1.5 : Bottom

1.6 : Right

1.7 : Left

The omitted rear view is a mirror image of the front view.

1 Claim, 7 Drawing Sheets
(7 of 7 Drawing Sheet(s) Filed in Color)
